UNITED STATES PATENT OFFICE

2,306,771

METHOD OF MAKING METALLIC TUBES

Bryant Bannister, Mount Lebanon, Pa., assignor
to National Tube Company, a corporation of
New Jersey

Application August 27, 1940, Serial No. 354,444

2 Claims. (Cl. 29—156)

This invention relates to a method of making metallic tubes, and particularly to that practice which is known in the art as "seamless."

The conventional method of manufacturing seamless pipes and tubes includes the casting of rectangular ingots which are rolled in a blooming mill into square blooms and then reduced to solid round bar in a bar mill, after which the bars are cut into desired lengths, cooled, and subjected to an operation which removes scale and surface defects. Such removal of scale and surface defects is known in the art of making metallic tubes as "conditioning," and comprises the removal of the outer surface of the bars to a certain depth in order to remove the surface imperfections, chiefly very fine cracks or seams. If these are not removed, they are expanded and enlarged in the finished tube. At the present time there are two widely used methods of conditioning; one utilizing oxygen torches and the other mechanical peeling, the first method burning off the surface metal and the second method machining or cutting it off. These bars, or "billets," as they are known in the art, are subsequently reheated, pierced, and rolled into pipes or tubes.

In my patent No. 2,216,718, issued October 8, 1940, and entitled "Manufacturing metallic tubular articles," there is disclosed a method of manufacturing metallic tubular articles which comprises casting a commercially-sized ingot of substantially circular cross-section, substantially reducing the over-all diameter of said ingot by a helical rolling operation whereby it is bloomed, and performing a tube-rolling operation on the bloomed ingot whereby a metallic tubular article of the desired size is obtained. The method of the co-pending application involves stripping the cast ingot while it is very hot, placing it in a conventional soaking pit and, after it has become properly equalized in temperature, charging it into a helical type of blooming mill whereby it is advanced helically between rolls which reduce its diameter to a size suitable for seamless mill operations. One of the advantages accruing from this practice is that there is a natural characteristic of a cylindrical ingot to have its least dense structure along the axial center line, and this enables the piercing point, which follows the path of least resistance, to follow closely the geometrical axis with the result that the reduced and pierced work-piece is remarkably concentric. That is to say, the wall thickness is extremely uniform. Another result accrues from the tendency of the core section

of the ingot to advance more rapidly than the exterior section, and this results in the formation of a symmetrical crater at the back or trailing end of the ingot as it advances into the mill. This results in the throwing of good metal surrounding the center section into the forward bloomed section, thereby increasing the amount of usable bloomed ingot. With the helical blooming mill of the co-pending application referred to, the number of work increments for a given reduction is from two to four times as great as in conventional blooming practice, each increment of reduction being correspondingly smaller. In addition, the forward movement of the metal increases as the reduction is made, which automatically increases the rate of reduction. Thus, such a helical blooming mill automatically provides gentler manipulation of the metal during the early stages of reduction, with an increase in rate of displacement as the ingot structure is refined. This is particularly important for the reason that the cast structure of the ingot is coarse-grained, with relatively weak bonds between the grains.

It is among the objects of the present invention to provide a method of manufacturing metallic tubular articles of the seamless variety, utilizing the aforesaid rotary blooming mill in the most efficient combination with subsequent rolling operations, which will result in a lowered production cost without decrease in quality.

Another object is the provision of a method of the class described, together with a mill layout for practicing the same which may utilize some equipment of existing design.

The foregoing and other objects will be apparent after referring to the drawings, in which:

Figure 1 is a longitudinal section of a cylindrical ingot of the type utilized in the practice of the invention of my co-pending application referred to and embodying a short pipe cavity;

Figure 2 is a plan of the helical rolling mill of said co-pending application, together with means at the outlet end thereof for "peeling" or removing surface defects from the billet;

Figures 3, 4, 5 and 6 are diagrammatic views, respectively, of a hot saw, reheating furnace, cross rolling mill, and a continuous tube mill wherein the wall thickness is reduced without reduction of the inside diameter; and

Figure 7 is a mill lay-out for the successful practice of the method of the present invention.

Referring more particularly to the drawings, the numeral 2 designates a cylindrical ingot which is to be worked in accordance with the teachings

of the present invention. This cylindrical ingot 2 is of a size and weight comparable to the rectangular ingots now in common usage and is preferably obtained by top casting. As shown in Figure 1, this cylindrical ingot 2 has adjacent the top thereof a conical pipe 2a which will be referred to more specifically hereinafter. While the ingot 2 is shown as being of the solid type, it will be readily understood by those skilled in the art that it may be provided with a hollow core (not shown). In accordance with the practice set forth in my Patent No. 2,216,718 entitled "Method of preparing billets," the cylindrical ingot is preferably of a size such as will produce two or more commercial lengths of pipe, and of a diameter of at least 16". Such an ingot, therefore, requires temperature equalization prior to rolling, and accordingly resort is had to soaking pit practice. After the temperature of the cylindrical ingot has been equalized, it is bloomed by a single pass through a helical type blooming mill, the reduction being from between 25% to 80% in diameter and down to a diameter of preferably 13" or less. The elongation accruing from the reduction is approximately in the same proportion as the square of the diameter of the entering work-piece is to the square of the diameter of the rolled billet neglecting the slight effect of the hole through the bloomed ingot.

For the purposes of the reduction mentioned immediately hereinbefore, I employ a pair of suitably driven rolls 3 which are cone-shaped. These rolls 3 are carried on shafts which converge onto the line of pass of the cylindrical ingot 2 and provide wide convergent surfaces 4 of rather acute angularity and relatively short surfaces 5 which are practically parallel with each other and, accordingly, the line of pass defined by the said rolls. While not shown in the drawings, the metal-working rolls 3 preferably have disposed therebetween a piercing point to reduce the work-piece to a tubular article during the blooming operation. From the foregoing, it will be perceived that the cylindrical ingot 2 entering the metal-working zone of the pass defined by the rolls 3 will be very materially reduced in diameter, subsequently "rounded-up" and then directed onto the outlet bed of the mill in materially elongated condition. Immediately after the work-piece or "bloom" emerges from between the outlet portions of the rolls 3, it comes into contact with a cutting device 10 generally indicated at 10.

This cutting device 10 comprises a housing in which there is reciprocably mounted, on slide-ways 12 a motor (not shown) driving a substantially vertical shaft 14 carrying a disk or cutting member 15. The disk 15 which rotates in a generally horizontal plane, has a cutting edge 16 that may be continuous or serrated in the manner of a milling cutter and is positioned by means of an automatic feed device 20 with its cutting edge in engagement with the helically advancing bloomed ingot or "billet," so as to obtain the depth of cut desired: for example, about an eighth of an inch. The automatic feed device 20 is connected to the motor (not shown) by means of a piston-rod 21 carrying a piston adapted to reciprocate in a cylinder 22. The piston is reciprocated in the cylinder 22 by means of fluid under pressure delivered thereto from a suitable source of supply.

It will be noted that the cutting disk 15 is yieldingly and not rigidly held against the work-piece, thereby preventing damage to the cutting disk in case the work-piece, as it is delivered from the rolls 3, should happen to be cobbled or warped.

In operation, the disk 15 is rotated by the vertical shaft 14 at such speed that the duration of contact with the hot metal of any portion of the cutting edge 16 is a small fraction of a second. By so regulating the speed of rotation of the disk 15, the cutting edge 16 is prevented from becoming overheated by its frictional engagement with the metal and because of the high temperature to which the work-piece is heated, which is approximately 2300 degrees Fahrenheit. The diameter of the disk 15 is such that the width of cut is considerably more than the advance of the work-piece per revolution. Consequently any portion of the cutting edge is in contact with the metal of the work-piece for only a small part of a revolution of the disk 15.

Normally the cutting edge 16 will cool during the time it is not engaging the metal of the work-piece. However, for certain kinds of metal it may be necessary to supply a cooling agent to the cutting edge 16, which can be done in any conventional manner. Two diametrically opposite cutting disks may be employed if desired; also, disks may be arranged in such a manner that the work-piece causes them to rotate, thus making the driving motors unnecessary.

A pair of guide disks 24 may be provided for steadyng the work-piece and, in addition, cooperate with the rolls 3 to helically advance it.

The combination of a rotating disk and the relative longitudinal movement of the rotating work-piece with respect to the rotating disk provides the essential elements for the successful conditioning of metal stock. No portion of the cutting edge is in contact with the metal long enough to reach an objectionably high temperature and between heating contacts there is sufficient time to cool the cutting edge effectively. Also, the rotation of the disk provides a true cutting or slicing action instead of a substantially plain shearing action that would occur if the disk were stationary. This is a definite advantage, as it is much more satisfactory to slice a plastic material such as steel, and particularly hot steel, than it is to shear it.

After the bloomed ingot or continuous billet or workpiece has passed the guide disks, it is cut into desired billet lengths. For the purpose of cutting, a conventional hot saw is preferably utilized, this being generally designated at 25 in Figure 3. In order to obtain the best results, it is preferable to reheat the cut billets in a re-heating furnace 26 which, so far as the purposes of the present invention are concerned, may be entirely conventional in design. After the cut billets, designated hereinafter at X, have acquired the desired temperature, they are withdrawn from the reheating furnace 26 and directed through a second piercing mill, which comprises a pair of rolls 30 which are barrel-shaped, or of the so-called "Mannesmann" type, providing short convergent surfaces 31 and relatively wide divergent surfaces 32. A mill of this design provides a thinning of the wall of the work-piece with some increase in diameter. The interior of the billet X is supported, while between the surfaces 31 and 32 of the second piercing mill rolls 30, by means of a mandrel or plug 34, which is supported in the desired position by means of a mandrel bar 35. If a product of smaller diameter is desired, rolls having converging faces as shown at 154 are provided.

After the billets X emerge from the second piercing operation, with an inner chamber approximately the same as that desired in the fin-

ished product accomplished by the cooperative action of the rolls 30, a cylindrical mandrel bar 48 is inserted in the billets X after which they are directed through a continuous tube mill, illustrated in Figure 6 as comprising a series of pairs of grooved rolls, the axes of each pair of which are parallel to each other and at substantial right-angles to the corresponding axes of the next adjacent pair. That is to say, the axes of the first pair of rolls, designated at 40, are at substantial right-angles to the axes of the next adjacent pair 42, and so on to the final pair, designated at 46. As will be observed from Figure 6, the third pair of rolls illustrated (i. e., those indicated at 46) are substantially parallel to the initial pair 40. Each pair of rolls of the continuous tube mill of Figure 6 defines a portion of a circular groove which is capable of effecting one-half of a complete increment of reduction of wall thickness over the entire billet X. It will be observed from an inspection of Figure 6 that a billet X and an interiorly disposed mandrel 48 have been broken away to indicate that the number of rolls between the second pair 42 and the final pair 46 may be increased. The function of the first two pairs of rolls 40 and 42 is, as before stated, to effect a complete increment of reduction of wall thickness over the entire billet X; while the function of the final pair of rolls 46 is to round-up the work-piece.

Referring to Figure 7 of the drawings, I have illustrated a mill lay-out, the units of which are so arranged that a wide range of tube sizes may be rolled without requiring the floor space necessary when using separate and distinct mills for the various sizes. This is possible because the rotary blooming mill has sufficient capacity to serve two second piercing mills. The schematic view of Figure 7 discloses the rolls 3 of the helical blooming mill referred to hereinbefore with the outlet bed thereof extending through transfer devices 140 and 142, which are designed to transfer tubes to sets of hot saws 25, from which the billets are cut from the initial elongated or continuous billet X. After cutting, the billets are transferred to adjacent cooling tables 145 and 146. Disposed adjacent the cooling tables 145 and 146 are bloom heating furnaces 148 and 149, respectively, which are only used when it is necessary to restore the blooms to hot-working temperature. Normally the blooms are directed through one of a pair of parallel tunnel furnaces 150 and 151, which extend, respectively, alongside the bloom heating furnaces 148 and 149. Thus, it will be seen that whether or not it is necessary to divert the blooms into bloom heating furnaces 148 and 149, they are moved through one of the tunnel furnaces 150 or 151 and subsequently expanded or sunk in accordance with conventional practice. For the purposes of sinking there is disposed at the exit end of the tunnel furnace 150 a rotary type of sinking piercing mill generally designated at 153 and comprising a pair of opposed cone-shaped rolls 154 having converging opposed faces and a mandrel or plug supported on a mandrel bar. From the rotary sinking piercing mill 153 the blooms are directed across a suitable transfer device 155 from which they are progressed through the continuous tube rolling mill of Figure 6, which is diagrammatically designated at 156 and shown as comprising eight stands. That is to say, the

continuous tube rolling mill generally designated at 156 will comprise not only the pairs of rolls 40, 42 and 46 of Figure 6, but five additional pairs, which will be disposed between the two last-named.

Referring again to Figure 7, it will be observed that disposed in parallelism with the rotary sinking piercing mill generally designated at 153, there is a rotary expanding piercing mill 160 facing in the opposite direction and comprising a pair of cone-shaped rolls 161 having diverging opposed faces and a mandrel or plug supported on a mandrel bar. According to this construction and arrangement, the function of the cone-shaped rolls 154 of the rotary sinking piercing mill 153 is to reduce the outside diameter of the billets, whereas the oppositely disposed cone-shaped rolls 161 of the rotary expanding piercing mill 160 are adapted to expand the outside diameter thereof. Therefore, dependent upon the desired product, the billets are directed through the proper tunnel furnace. In the manner of the ancillary instrumentalities of the rotary sinking mill 153, the rotary expanding mill 161 employs a transfer device 165 and a continuous tube rolling mill diagrammatically designated at 166, the latter of which, like the continuous tube rolling mill 156, is shown as comprising eight stands.

According to the foregoing lay-out, provision is made for rapidly reducing cylindrical cast ingots, with a minimum of time and expense, to a tubular shell which may be finished in accordance with conventional finishing operations which, as such, form no part of the present invention and, accordingly, are neither illustrated nor described.

While I have shown and described certain specific embodiments of the present invention, it will be seen that I do not wish to be limited exactly thereto, since various modifications may be made without departing from the scope of the invention, as defined by the following claims.

I claim:

1. The method of manufacturing metallic tubular articles which comprises casting a commercial-sized ingot of substantial circular cross-section, substantially reducing the overall diameter of said ingot by a helical rolling operation by which it is bloomed and pierced, conditioning the surface of said bloom as it emerges from said helical rolling operation, cross-rolling said bloom to partially reduce the wall thickness thereof, then inserting a mandrel in said cross-rolled blank, and reducing the wall thickness to that desired in the finished product by rolling it in a continuous tube mill.

2. The method of manufacturing metallic tubular articles which comprises casting a commercial-sized ingot of substantial circular cross-section, substantially reducing the overall diameter of said ingot by a helical rolling operation by which it is bloomed and pierced, conditioning the surface of said bloom as it emerges from said helical rolling operation, cross-rolling said bloom to partially reduce the wall thickness thereof and obtain an inner diameter which is approximately that desired in the finished product, then inserting a mandrel in said cross-rolled blank, and reducing the wall thickness to that desired in the finished product by rolling it in a continuous tube mill.

BRYANT BANNISTER.
